CLAIM

The ornamental design for an interactive computerized system, as shown and described.

DESCRIPTION

FIG. 1 is a front, top and side perspective view of the interactive computerized system according to my new design;

FIG. 2 is a front, top and side perspective view into an alternate position of the system shown in FIG. 1;

FIG. 3 is a rear, top and side perspective view of the system shown in FIG. 1;

FIG. 4 is a rear elevation view of the system shown in FIG. 1;

FIG. 5 is a front elevation view of the system shown in FIG. 1; and,

FIG. 6 is a right side elevation view of the system shown in FIG. 1, the left side elevation view being a mirror image.

The portions of the interactive computerized system shown in broken lines form no part of the claimed design.
